UNITED STATES PATENT OFFICE.

JOHN P. DORNEY, OF WATERVLIET, NEW YORK.

COMBINATION-GAGE.

1,379,253.

Specification of Letters Patent. Patented May 24, 1921.

Application filed December 3, 1919. Serial No. 342,162.

To all whom it may concern:

Be it known that I, JOHN P. DORNEY, a citizen of the United States, and a resident of Watervliet, in the county of Albany and 5 State of New York, have invented an Improvement in Combination-Gages, of which the following is a specification.

This invention relates to a combination measuring instrument especially adapted to 10 be used in the tool room of a machine shop where a high degree of accuracy is essential.

By using my invention in conjunction with an ordinary combination square or protractor, an instrument is obtained which may 15 be used as a substitute for a number of expensive measuring devices which usually form part of the equipment of a tool room or a machine shop.

For instance, my invention may be applied 20 so as to act as a vernier caliper, vernier depth gage, height gage, bevel protractor and the like.

Figure 1 is a perspective view of my vernier attachment;

25 Fig. 2 is a vertical section of the same;

Fig. 3 shows the invention in use as a vernier caliper;

Fig. 4 is a side elevation of a special blade used in connection with my invention;

30 Fig. 5 illustrates the application of the invention to a protractor; and

Fig. 6 illustrates the use of the invention as a height gage.

Reference will be made in the following 35 description to the accompanying drawings which illustrate the preferred embodiment of my invention and in which like numerals represent corresponding parts throughout the several views.

40 The attachment having a body 10 is preferably made from a rectangular piece of Bessemer steel through which are transversely milled at spaced intervals, two grooves 11 and 12, which are lapped to form 45 a snug-sliding fit with measuring blades.

The measuring blades are preferably three in number and of such lengths as are ordinarily used in making measurements common to the particular machine shop, usually 50 such lengths as 2, 4 and 8 inches being desirable. A special blade 15 suitably graduated and having an outlying projection terminating in a sharp point 16, is also provided for use in conjunction with a height 55 gage. Near the base of the body 10 is also

milled a groove 17, of such width and depth as to fit the blade of an ordinary 12 inch combination square or 12 inch steel scale. Over the groove 17 is attached a cover-plate 19, which is secured to the body member 10 60 by means of machine screws 20 and this plate not only acts as a retainer for the blade of the square, but also contains a bearing for the cam 21 mounted on a shaft 22 to which is secured a knurled thumb piece or 65 knob 23. The other bearing for shaft 22 is in the body member 10. The thumb piece 23 and cam 21 being larger than shaft 22 act to retain the cam in position.

The body 10 of the attachment is bored 70 longitudinally and the rod 24 extends through the hole thus formed. The rod 24 is formed with slots 25 and 26, which are adapted to register with the grooves 11 and 12. The longitudinal position of the rod 24 75 may be varied by means of a nut 27, which is secured to the threaded end of said rod. The nut 27 is recessed for the reception of a spring 28, which is compressed between the body 10 and the surface of the recess in nut 80 27 and tends to urge the rod 24 outwardly.

Assume that the attachment 10 is to be applied to the blade 18 of an ordinary combination square as illustrated in Fig. 6, which is accomplished by turning the knob 23, until 85 the small portion of cam 22 is presented to the blade of the square, then inserting the blade of the square into the slot 17 and turning the knob 23 until the cam 22 tightly holds the attachment in position on the blade 18. 90 The blades 15 and 29 are then inserted in the body 10 by first making the slots 25 and 26 of rod 24 register with the grooves 11 and 12 respectively, then inserting said blades within these grooves and tightening the nut 27. 95 This will compress the spring 28, which will yieldingly urge the rod 24 outwardly so as to clamp the blades in place.

It will be noted that the blades 15 and 29 are graduated to small dimensions and that 100 corresponding vernier graduations are made on the beveled surfaces 13 and 14 which are adjacent to the slots 11 and 12 so that a vernier reading to a fractional subdivision of such graduations may be readily made. 105

Figs. 3, 5 and 6 illustrate several ways in which this measuring device may be applied, but it will be understood that many other applications will occur to those familiar with testing work in the machine 110

shop or on the surface plate of the inspection or tool room.

Fig. 3 illustrates the use of the invention as a vernier caliper, and in this case, the 5 attachment 10 is applied to the blade 18 of the square as previously described and is secured in place thereon in a suitable position for the work at hand.

The blade 29, inserted in slot 11, is then 10 projected until contact is made with the base 30 of the combination square and the vernier reading at 13 is then taken and recorded. The blade 29 and square 13 is then used in the same manner as a caliper.

15 The cylindrical piece A, contacts on one side with the base 30 of the square, and on the other side with the end of the blade 29 so that by taking the vernier reading at 13 and subtracting it from the first reading, the 20 diameter of the piece A may be accurately ascertained.

The use of the device as a height gage is illustrated in Fig. 6. Assume that it is desired to determine the height of a certain 25 object above the surface plate indicated at C. Attach body 10 to the blade of the combination square as previously described and set the square on a surface plate opposite the piece to be measured and adjust 30 the body to a position slightly in excess of the height to be determined, insert the blade 29 in the groove 12, and advance the blade until it meets the surface plate and record the vernier reading.

35 The blade 29 is then withdrawn and the object to be measured is placed upon the surface plate beneath the blade, which is again projected to contact with the upper surface of the object. This reading is also 40 taken and the difference of the two readings gives the height of the object measured.

For the accurate checking of lines such as the line B, the blade 15 is used, it being 45 moved until its point 16 engages the line and its vernier reading then taken. Subtract this vernier reading from the height of the body 10 above the surface plate as obtained from blade 29 and the remainder will give 50 the distance from the line to the surface plate.

Fig. 5 shows the body 10 applied to the blade of a protractor and it is used in connection with the special blade 15 to prove the regularity of a surface D. The blade of 55 the protractor is first set to the given angle and the body 10 may be then moved up and down and a light mark made by the point 16 will indicate the regularity of the taper of the surface D.

60 Many other applications of the invention will occur to those skilled in the art and it will be seen that a precision instrument is obtained, which is cheap to manufacture, accurate in operation and which is capable of

replacing a number of expensive measuring 65 instruments now generally used.

Having described my invention, what I claim as new and desire to secure by Letters Patent, is:—

1. An attachment for measuring instruments comprising a body, said body being cut to form a large groove adapted to receive a supporting blade, and a small groove adapted to receive a measuring blade, a cover plate for said large groove, a cam journaled 75 in said cover plate and body for securing said body in position and a rod slidably longitudinally of said body and co-operating with said small groove for yieldingly holding said measuring blade in adjusted position. 80

2. An attachment for measuring instruments comprising a body, said body being cut to form one or more grooves having a sliding fit for measuring blades, a rod slidably longitudinally of said body and cut with a like number of recesses, a nut at one end of said rod having a recessed chamber and a spring inserted in said chamber whereby the 90 adjustments of said nut will exert a yielding force on said rod for holding the blades in adjusted position in said grooves. 90

3. An attachment for measuring instruments comprising a body cut to form a large groove and a small groove, said large 95 groove being adapted to receive a supporting blade, a graduated measuring blade having a sliding fit in said small groove, a cover-plate for said large groove, means journaled in said cover-plate and body for retaining 100 said body in adjusted position on the supporting blade, and means adjustable longitudinally of said body for retaining said graduated blade in adjusted position. 100

4. An attachment for measuring instruments comprising a body cut to form a large groove and a small groove, said large groove being adapted to receive a supporting blade, a graduated measuring blade having a sliding fit in said small groove, a cover-plate 110 for said large groove, means journaled in said cover-plate and body for retaining said body in adjusted position on the supporting blade, and means adjustable longitudinally of said body for retaining said graduated 115 blade in adjusted position, said body provided with a vernier for measuring fractional subdivisions of said graduations.

5. An attachment adapted to be adjustably secured to the blade of a square, protractor 120 or the like, comprising a body member, a graduated blade, a graduated pointer, and means on said body for holding said blade and pointer in adjusted position, said body provided with vernier graduations for measuring fractional subdivisions of the readings on said blade and pointer. 125

JOHN P. DORNEY.
